UNITED STATES PATENT OFFICE.

JOHN A. LAMONT, OF CHICAGO, ILLINOIS, ASSIGNOR TO AMERICAN STEEL FOUNDRIES, OF CHICAGO, ILLINOIS, A CORPORATION OF NEW JERSEY.

TRUCK BOLSTER.

Application filed March 23, 1927. Serial No. 177,488.

This invention relates to an improved bolster structure for railroad car trucks, and more particularly to one which embodies the general features of the standard A. R. A. type and which is provided with an internal reinforcing beam depending from the upper portion of the bolster underlying the center plate, in a manner to afford a support for the center plate.

Truck bolsters of this type are in effect box shaped girders which are supported at their outer ends usually on resilient supports carried by the truck side frames and are provided intermediate their length with a center plate which supports the load of one end of the car. (The standard A. R. A. bolsters are constructed with upper and lower web portions connected by side walls to form a rectangular beam, the lower member being a tension member and the upper member being a compression member. In order to provide sufficient support beneath the center plate, various practices have been resorted to, in that some means are usually provided in addition to the upper web portion, the lower web portion and the side walls. In some instances, it has been the practice to provide a cylindrical column beneath the center plate which forms a supporting column between the upper web portion and the lower web portion.

The present invention provides a structure in which the load imparted to the center plate is more uniformly distributed throughout the length of the bolster, and is one in which the load is imparted to the side walls, the upper web portion being provided with a reinforcing beam beneath the center plate which renders the structure strong enough to support the load without providing a supporting column for the center plate between the upper and lower web members. The reinforcing beam is in practice a U-shaped reinforcing beam having a bottom member and side walls formed integral with the upper web portion of the bolster structure and forming therewith a secondary beam, the side walls being spaced from the side walls of the bolster.

The bottom member of the secondary beam which underlies the center plate is provided with a recess or pocket for engaging and supporting the king pin.

Another advantage is that the various features referred to above may be incorporated

in a bolster structure of the standard A. R. A. type having generally the structural features provided in such a bolster.

These and other advantages are accomplished by means of the arrangement disclosed on the accompanying sheet of drawings, in which—

Figure 1 is a side elevation of a truck bolster embodying the features of my invention, the view being partially in cross section to reveal the internal structure;

Figure 2 is a plan view of the structure shown in Figure 1, this figure also being partially in cross section to reveal the internal structure, the figure being taken on the line 2—2 as shown in Figure 1; and

Figure 3 is a cross sectional view taken through the center of the bolster.

The various novel features of the invention will be apparent from the following description and drawings, and will be particularly pointed out in the appended claims.

Referring to the drawing, it will be noted that my invention is disclosed in connection with a truck bolster designated generally as 10, which is provided with a top web portion 11 and a bottom web portion 12 and side walls 13. The outer ends of the bolster are provided with vertical ribs 14 which form the guiding slots 15 for engagement with the guideway provided in the side frames of the car truck not disclosed. The upper web portion is provided with openings 16 on opposite sides of the center, and the bottom web portion with openings 17 on opposite sides, suitably reinforced by circumferential flanges 18 and 19 respectively. In the middle portion of the upper web, the center plate 20 is provided which consists of an upstanding circumferential flange 21 and a center opening 22 which is adapted to receive the king pin. The king pin opening is provided with flanges extending above and below the web as at 23 so that the king pin will have a bearing surface of increased area.

The car bolster thus far described is of the standard A. R. A. type and constitutes an old structure in the art. In addition to the elements set forth, my invention contemplates a reinforcing beam depending from the upper web portion 11 and underlying the center plate 20, attention being directed to Figure 3 whereby it will be noted that the reinforcing beam is formed integrally with the upper web portion 11 and

comprises side walls 24 and a bottom web 25. The bottom web is of a general arch shape and is provided centrally with a cup portion 26 for fixing the lower end of the 5 king pin, the cup portion having a hole 27 therethrough in alignment with the king pin opening 22 in the upper web portion, and the hole 28 in the bottom web portion, so as to permit removal of the king pin by 10 the insertion of a tool therethrough in the event of breakage, wear or when bent. The reinforcing beam, it will be noted, constitutes a secondary beam support primarily for the center plate whereby the bottom web 15 portion 25 acts in the capacity of a tension member, and the upper web portion, which is a portion of the web 11, serves as a compression member, the walls 24 being spaced laterally from the side walls 13 of the bolster 20 as shown in Figure 3, the walls 24, however, diverging upwardly where they are united with the upper web portion. The upper web portion, by reference to Figure 3, is preferably increased in thickness outwardly 25 as shown at 29 so that extra strength is provided in imparting and carrying the load from the center plate to the side walls 13 of the bolster.

Also, in this construction the side walls 30 act to deliver the load to the bottom web member and in order to better provide for the distribution uniformly over the bottom area, the bottom web portion is thicker as at 30 adjacent the point where it joins with 35 the side wall, in which case the central portion designated 31 may be reduced to a minimum. The side walls 24 of the reinforcing beam extend diagonally upward toward the top portion and join the top portion at a 40 point adjacent the flange 18 which surrounds the opening 16, whereby ample strength is provided in the bolster at a point substantially removed from the actual area of the center plate 20. It will be noted that the 45 bottom web 25 of the reinforcing beam terminates as at 32, whereby the opening 33 is provided to conform to the standard A. R. A. construction.

From the above description, it will be 50 readily recognized that I have provided a bolster which embodies all the features of the standard A. R. A. bolster, and in addition is provided with a reinforcing beam underlying the center plate which will provide 55 sufficient strength and serve as a support for the load carried by the center plate, and will serve to distribute the load equally throughout the entire bolster structure, the load being carried uniformly by the walls 60 and upper and lower web portions throughout their entire length and in this way avoid any concentrated application of load.

I claim:

1. A railroad car truck bolster structure, 65 comprising an upper web portion and side

walls, and a reinforcing beam having side walls depending from said web portion and positioned below the center plate of said bolster.

2. A railroad car truck bolster structure, 70 comprising an upper web portion and side walls, and an integral reinforcing beam having side walls depending from said web portion and positioned below the center plate. 75

3. A railroad car truck bolster structure, comprising an upper web portion and side walls, and a reinforcing beam having side walls depending from and extending longitudinally of said web portion, positioned 80 under the center plate of said bolster and spaced laterally from said walls.

4. A railroad car truck bolster structure, having a center plate thereon and comprising an upper web portion and side walls 85 integral therewith, and a reinforcing beam having side walls depending from said web portion and underlying said center plate, said reinforcing beam forming with said web portion a support for said center plate. 90

5. A railroad car truck bolster, comprising an upper web portion and side walls, said bolster having a center plate carried by said side walls, said web portion having a reinforcing beam depending therefrom and underlying said center plate, said beam having side walls and a tension member. 95

6. A railroad car truck bolster, comprising an upper web portion and side walls, said bolster having a center plate carried by said 100 side walls, said web portion having a reinforcing beam depending therefrom underlying said center plate and having side walls spaced from said first named side walls.

7. A railroad car truck bolster, comprising an upper web portion and side walls, said bolster having a center plate carried by said side walls, said web portion having a reinforcing beam depending therefrom underlying said center plate, and spaced from 105 said walls, said web portion between said reinforcing beam and said walls increasing in thickness toward said walls. 110

8. A railroad car truck bolster structure, comprising an upper web portion and side walls, a center plate formed on said bolster, and a reinforcing beam depending from said web portion underlying said center plate, said reinforcing beam having side walls spaced from said first named side walls and aiding to support the load on said center plate and also being provided with an opening for receiving and supporting the king pin. 115

9. A railroad car truck bolster structure, comprising upper and lower web portions and side walls forming a rectangular box shaped girder beam, a center plate on said upper web portion, a reinforcing beam underlying said center plate comprising a lower 120

web portion and side walls and forming with a portion of said upper web portion a second beam for supporting said center plate.

10. A railroad car truck bolster having a center plate on the top portion thereof, a reinforcing beam depending from the under side of said center plate and forming a cen-

tral support therefor, said center plate being carried by the side walls of said bolster, and said reinforcing beam having side walls 10 spaced from said first named side walls.

Signed at Chicago, Illinois, this 10th day of March, 1927.

JOHN A. LAMONT.
